UNITED STATES PATENT OFFICE.

FRANCIS JOSEPH McAVOY, OF NEWARK, NEW JERSEY.

AUXILIARY TRAIN-CONTROLLING MEANS.

Application filed November 30, 1920. Serial No. 427,314.

To all whom it may concern:

Be it known that I, FRANCIS JOSEPH McAVOY, a citizen of the United States, and a resident of Newark, in the county of Essex

5 and State of New Jersey, have invented a new and Improved Auxiliary Train-Controlling Means, of which the following is a full, clear, and exact description.

The invention relates to air brakes, and 10 its object is to provide a new and improved auxiliary train controlling means for passenger and freight trains and arranged to enable the engineer to quickly and accurately control the train.

15 Another object is to apply the brakes throughout the several cars of the train and practically at the same time and with uniform force.

Another object is to permit installation of 20 the auxiliary train controlling means on trains now equipped with the New York, Westinghouse, or other type of brake system.

With these and other objects in view, the 25 invention consists of certain novel features of construction, as hereinafter shown and described and then specifically pointed out in the claims.

A practical embodiment of the invention 30 is represented in the accompanying drawings forming a part of this specification, in which similar characters of reference indicate corresponding parts in all the views.

Figure 1 is a side elevation of the improved auxiliary train controlling means arranged in connection with a brake mechanism of the New York type;

Figure 2 is an enlarged side elevation with parts shown in section of the auxiliary train controlling means with the parts in release position;

Figure 3 is a side elevation of the brake and release valve in service position, parts being shown in section;

45 Figure 4 is a side elevation of the brake and release valve in emergency position;

Figure 5 is a sectional side elevation of the brake and release valve in lap position;

Figure 6 is a plan view of the same in 50 release position;

Figure 7 is a cross section of the same on the line 7—7 of Figure 4;

Figure 8 is a plan view of the engineer's valve;

55 Figure 9 is a side elevation of the same;

Figure 10 is a diagrammatic view of the improved auxiliary train controlling means and showing the electric connection with the engineer's valve;

Figure 11 is a side elevation of a modified 60 form of the auxiliary train controlling means;

Figure 12 is an enlarged sectional side elevation of the valved coupling for the auxiliary pipe used for supplying compressed 65 air from the main reservoir of the locomotive to the auxiliary main reservoir of the auxiliary train controlling means;

Figure 13 is a side elevation of a portion 70 of the tubing for carrying the electric conductors, with the floor portion of a car shown in section;

Figure 14 is an enlarged sectional plan view of one of the couplings for the electric conductors, the section being on the line 75 14—14 of Figure 15; and

Figure 15 is a perspective view of the same with the coupling members shown disconnected.

The air compressor 20 on the locomotive 21 80 is connected by a pipe 22 with a main reservoir 23 connected by a pipe 24 with another main reservoir 25 connected by a pipe 26 with an engineer's valve 27 of usual construction except for the switching means 85 hereinafter more fully explained. The engineer's valve 27 is connected by a pipe 28 with the train pipe 29 extending along the several cars of the train and connected at each car with the usual air brake equipment 90 thereon including notably a triple valve 30, a brake cylinder 31 and an auxiliary reservoir 32 coacting in the usual manner to apply and release the brakes on the engineer correspondingly actuating the engineer's 95 valve 27. In the connection between the train pipe 29 and the triple valve 30 is arranged a reducing valve 33 to allow of maintaining a higher pressure in the train pipe 29 than in the auxiliary reservoir 32. 100

In case the auxiliary train controlling means is used on a freight train then the said means is located on the caboose, and for passenger trains each car is preferably equipped with the auxiliary train controlling means. In each case use is made of an auxiliary main reservoir 40 having approximately the same air pressure as that in the main reservoirs 23 and 25, say 100 pounds. The auxiliary main reservoir 40, as shown 110

in Figure 1, is connected by a pipe 41, having a check valve 42, with the train pipe 29 to allow of charging the auxiliary main reservoir 40 with the pressure from the main reservoirs 25 and 23 on the engineer correspondingly manipulating the engineer's valve 27, that is, the auxiliary main reservoir 40 is charged, say, with 100 lbs., while the auxiliary reservoir 32 is charged with 75 lbs. The check valve 42 prevents return flow of air pressure from the main reservoir tank 40 on a reduction of pressure in the train pipe 29 when applying the brakes.

The main auxiliary reservoir 40 is connected 15 by a pipe 45 with a brake and release valve 46 of any approved construction, preferably, however, similar to the brake and release valve used in the New York air brake system for enabling the engineer to release 20 the locomotive brakes independently of the applied brakes on the cars of the train. The brake and release valve 46 is connected by a pipe 47 with the train pipe 29, and the two pipes 45 and 47 are provided with manually controlled cut-out valves 48 and 49 normally in open position.

The brake and release valve 46 is shown in detail in Figure 5 and comprises a valve casing 50 having a valve seat 51 on which 30 is mounted to slide a slide valve 52 provided at its under side with a cavity 53. The slide valve 52 controls ports 54, 55, 56, of which the port 54 connects with a nipple 58 coupled to the pipe 47; the port 55 connects with a nipple 60 coupled to the atmosphere; and the port 56 connects with an exhaust chamber 59 having an outlet 57 leading to pipe 45 and the reservoir 40. The slide valve 52 is provided with a pin 61 engaged by a forked arm 62 attached to a shaft 63 journaled in the valve casing 50. On the outer end of the shaft 63 is secured an operating arm 64 normally held in emergency position by the action of a spring 65. The slide valve 52 is adapted to be moved 45 into release position, as shown in Figure 2, or into service position as shown in Figure 3, or into lap position as shown in Figure 5, and this movement of the brake and release valve 46 is in unison with the corresponding movement of the engineer's valve 27 in the cab of the locomotive 21. Thus when the engineer moves the engineer's valve 27 into release, service, lap or emergency position then the brake and release valve 46 moves into corresponding release, service, lap or emergency position to apply and release the brakes at the rear portion of the freight train at the same time that 60 the brakes are applied and released on the front portion of the train through the action of the engineer's valve 27. It is understood that the release position of the valve is adapted to connect the reservoir 40 with the train line; the service position of the

valve is such as to connect the train line with the atmosphere but not with a full uncovering of the ports; the emergency position of the valve is such as to connect the train line with the atmosphere with as full 70 as possible uncovering of the ports, so as to permit a quick reduction of the pressure of the train line; and the lap position of the valve is such as to shut off all connection between the train line, the atmosphere and 75 the reservoir 40 so as to result in the maintenance of whatever position has just previously been taken in the system.

In order to move the slide valve 52 from emergency position into release, service or lap position, use is made of pneumatic means arranged as follows: On a bracket 70 attached to the valve casing 50 are arranged three cylinders 71, 72 and 73 in which are mounted to reciprocate pistons 74, 75 and 76 provided with piston rods 77, 78 and 79 extending through the corresponding heads 80, 81 and 82 on the rear ends of the cylinders 71, 72 and 73. The piston rods 77, 78 and 79 are provided within the cylinders 90 71, 72 and 73 with stop collars 83, 84 and 85 adapted to abut against the heads 80, 81 and 82 to limit the rearward movements of the pistons 74, 75 and 76 in the cylinders 71, 72 and 73. The outer ends of the piston rods 77, 78 and 79 are provided with heads or buttons 86, 87 and 88 adapted to engage a sleeve 90 forming part of the handle 64 and being preferably secured thereon by a bolt 91. When the piston 74 is moved rearward in the cylinder 71 until the stop collar 83 strikes the head 80 then the button 86 has moved the handle 64 into release position against the tension of the spring 65, as shown in Figure 2. When the piston 75 is moved rearward in its cylinder 72 until its stop collar 84 abuts against the head 81, as shown in Figure 3, then the button 87 is in position to hold the handle 64 in service position after the handle 64 moves from release position to service position. In a like manner when the piston 76 is moved rearward in its cylinder 73 until the stop collar 85 abuts against the head 82 then the button 88 has moved the handle 64 from service 110 position to lap position, as shown in Figure 5. When the several pistons 74, 75 and 76 are in foremost positions, as shown in Figure 4, then the spring 65 has pulled the handle 64 into emergency position for an emergency 115 application of the brakes.

In order to move the pistons 74, 75 and 76 in unison with the engineer's valve 27, the following arrangement is made: From the auxiliary main reservoir 40 extends a 125 pipe 100 provided with a reducing valve 101, and this pipe 100 is connected with air chambers 102, 103 and 104 connected by pipes 105, 106 and 107 with the forward ends of the cylinders 71, 72 and 73. Each 130

of the air chambers 102, 103 and 104 is provided with valve seats 108, 109 and 110, controlled by valves 111, 112 and 113 connecting the pipe 100 with the corresponding pipes 105, 106 and 107 or disconnecting the same. Normally the valves 111, 112 and 113 are held on their seats by springs 114. The valves 111, 112 and 113 are engaged at the upper ends of their valve stems by cores 120, 121 and 122 of solenoids 123, 124 and 125 mounted on top of the air chambers 102, 103 and 104. The lower ends 126, 127 and 128 of the cores 120, 121 and 122 control valve seats 130, 131 and 132 connecting the air chambers 102, 103 and 104 with exhaust chambers 133, 134 and 135 formed in the upper portion of the air chambers 102, 103 and 104. The exhaust chambers 133, 134 and 135 are provided with exhaust 20 apertures 136, 137 and 138 leading to the atmosphere. It is understood that normally the valves 111, 112 and 113 are held in closed position by their springs 114 and the cores 120, 121 and 122 are held in uppermost position by the said valves. Now in case any one of the solenoids 123, 124 or 125 is energized then its core 120, 121 or 122 moves downward and in doing so it moves the corresponding valve 111, 112 or 113 into open position thereby connecting the pipe 100 with the corresponding pipe 105, 106 or 107 to admit compressed air to the corresponding cylinder 71, 72 or 73 to move the piston 74, 75 or 76 rearward in such cylinder to actuate the slide valve 52 correspondingly, as above explained. As soon as the solenoid 123, 124 or 125 is de-energized then the corresponding valve 111, 112 or 113 is returned to uppermost position by the spring 114 and consequently the corresponding core 120, 121 or 122 is raised and moved off the seat 130, 131 or 132 to allow air from the corresponding cylinder 71, 72 or 73 to promptly escape by way of the pipe 105, 106 or 107, the chamber 102, 103 or 104 and the exhaust chamber 133, 134 or 135, thereby permitting return movement of the piston 74, 75 or 76 in its cylinder 71, 72 or 73. The solenoids 123, 124 and 125 are controlled by switching means on the engineer's valve 27 and the said solenoids are connected by wire 139 with a source of electrical energy 140 preferably in the form of a storage battery charged from a generator 141 preferably actuated from an axle 142 of the caboose or car on which the auxiliary train controlling means are installed. The switching means from the engineer's valve 27 are arranged as follows: On the handle of the engineer's valve 27 is secured an insulated contact arm 151 connected by a wire 152 with the source of electrical energy 140. The contact arm 151 is provided on its free end with a spring-pressed button 153 adapted to engage segmental contacts 155, 156, 157 and 158, insulated one from the other and mounted on a suitable bracket 160 held insulated on the casing 161 of the engineer's valve 27. The segmental contact 155 is connected by a wire 165 with the solenoid 123, a wire 166 connects the segmental contact 157 with the solenoid 124, and a wire 167 connects the segmental contact 156 with the solenoid 125. When the handle 150 of the engineer's valve 27 is in release position then the button 153 of the contact arm 151 is in engagement with the segmental contact 155 and consequently the solenoid 123 is energized to connect the pipe 100 with the cylinder 71. When the handle 150 is moved into service position then the button 153 of the contact arm 151 is moved in engagement with the segmental contact 157 and consequently the solenoid 124 is energized to connect the pipe 100 with the cylinder 72. When the handle 150 is moved from service position to lap position then the button 153 is in engagement with the segmental contact 156 and consequently the solenoid 125 is energized to connect the pipe 100 with the cylinder 73. When the handle 150 is moved into emergency position then the button 153 moves into engagement with the segmental contact 158, that is, out of engagement with the other segmental contacts 155, 156 and 157 and consequently the several solenoids 123, 124 and 125 are de-energized to allow the several pistons 74, 75 and 76 to return forward to normal position and thereby allow the spring 65 to move the handle 64 and with it the valve 52 into emergency position for an emergency application of the brakes. From the foregoing it will be seen that the brake and release valve 46 automatically assumes the various positions into which the engineer's valve 27 is moved by the engineer in charge of the train. The operation of the brake and release valve 46 is practically simultaneous with that of the engineer's valve 27 and consequently the brakes are applied or released practically simultaneously in both the front and rear portions of the train. The action of the engineer's valve 27 for releasing the brakes and applying the brakes for both service and emergency applications is well known, and, as the action of the brake and release valve 46 is in unison with the engineer's valve and functions in the same manner, further description of the action of the brake and release valve 46 is not deemed necessary.

It is understood that the positions "running," "holding" and "lap" of the engineer's valve are embraced in the single segmental contact 156 and consequently the brake and release valve 46 only assumes the single po-

sition "lap" whenever the engineer's valve is moved into running," "holding" or "lap" position.

It will be noticed that in case the electric connection between the engineer's valve 27 and the solenoids is broken, the several solenoids are de-energized and the air is allowed to escape from the three cylinders 71, 72 and 73 to cause an emergency application of the air brakes.

It will also be noticed that by the arrangement described the engineer is enabled to quickly and properly control the train irrespective of its length. It will further be noticed that the auxiliary train controlling means may be readily connected with air brake systems such as New York and Westinghouse, without any alterations in such systems.

As previously stated, the auxiliary train controlling means are preferably applied to each car of a passenger train, but any one of the auxiliary train controlling means in a car can be cut out on closing the valves 48 and 49 in the pipes 45 and 47 connecting the brake and release valve 46 with the auxiliary main reservoir 40 and the train pipe 29, respectively.

In the modified form shown in Figure 11, the main auxiliary reservoir 40 is directly charged from the main reservoir 25 by the use of a separate pipe 170, similar to the train pipe 29, and extending along the several cars of the train. This pipe 170 is connected by a pipe 171 with the auxiliary main reservoir 40, as plainly shown in Figure 11. The pipe 170 is provided with a coupling 175 between adjacent cars and this coupling 175 consists of two coupling members 176, 177 adapted to be connected with each other or disconnected and similar to the ordinary couplings on the train pipe. The coupling members 176 and 177 are provided on their contacting faces with registering valve seats 178 and 179 (see Figure 12) normally open but adapted to be closed by ball valves 180 and 181 normally seated in seats 182 and 183 arranged on the coupling members 176 and 177. The ball valves 180 and 181 are pressed on by springs 184 and 185 and are normally in contact with each other, thus holding the valves off their seats 178, 179. Now in case the coupling members 176 and 177 become accidentally separated, then the ball valves 180 and 181 are moved into closed position on the seats 178 and 179 by the action of the springs 184 and 185 thereby preventing escape of main reservoir pipe pressure. It will be noticed that by the arrangement described the usual angle cocks can be dispensed with on the pipe 170.

The circuit wires 152, 165, 166 and 167 are insulated and preferably extend through a tube 190 extending along the cars in the train (see Figure 13), and flexible coupling

tubes 191 are provided at the adjacent ends of the sections of the tube 190 at adjacent cars. The flexible coupling tubes 191 are connected with each other at their adjacent ends by a coupling 195 made in two sections 70 196, 197, shown in Figures 14 and 15. The coupling sections 196 and 197 are made of a suitable insulating material and are provided with spring sockets 200, 201 and connecting pins 202, 203 projecting from the 75 ends of the sections 196, 197 and engaging the corresponding sockets 201, 200 on moving the sections 196 and 197 into coupling engagement, as shown in Figure 14. The coupling sections 196 and 197 are provided 80 with caps 205, 206 connected with the flexible tubes 191 and through which extend the corresponding ends of the wires 152, 165, 166 and 167 to connect with the binding posts 210 and 211, of which the binding 85 posts 210 are connected with the sockets 200 and the pins 202, and the binding posts 211 are connected with the sockets 201 and the pins 203.

Having thus described my invention, I 90 claim as new and desire to secure by Letters Patent:—

1. An auxiliary train controlling means, comprising an auxiliary main reservoir located on a car in the train and adapted to 95 be charged from the main reservoir on the locomotive, and a brake and release valve operating in unison with the engineer's valve and connected with the train pipe and the said auxiliary main reservoir. 100

2. An auxiliary train controlling means, comprising an auxiliary main reservoir mounted on a car in the train and adapted to be charged from the main reservoir on the locomotive, a brake and release valve 105 mounted on the said car and connecting the said auxiliary main reservoir with the train pipe, and actuating means controlled by the engineer's valve in the locomotive and actuating the said brake and release valve in 110 unison with the engineer's valve.

3. An auxiliary train controlling means, comprising an auxiliary main reservoir mounted on a car in the train and adapted to be charged from the main reservoir on 115 the locomotive, a brake and release valve mounted on the said car and connecting the said auxiliary main reservoir with the train pipe, pneumatic actuating means for the said brake and release valve, and controlling means controlled from and moving in unison with the engineer's valve, the said controlling means connecting the said pneumatic actuating means with the said auxiliary main reservoir. 120

4. An auxiliary train controlling means, comprising an auxiliary main reservoir mounted on a car in the train and connected with the train pipe to be charged with auxiliary main reservoir pressure, a brake and 130

release valve mounted on the said car and connected with the train pipe and with the said auxiliary main reservoir, a spring adapted to move the said brake and release valve into emergency position, pneumatic actuating means moving the said brake and release valve into release, lap and service positions, and connecting means connecting the said auxiliary main reservoir with the said pneumatic actuating means to operate the latter, the said connecting means operating in unison with the engineer's valve in the cab of the locomotive.

5. An auxiliary train controlling means, comprising an auxiliary main reservoir mounted on a car in the train and connected with the train pipe to be charged with auxiliary main reservoir pressure, a brake and release valve mounted on the said car and connected with the train pipe and with the said auxiliary main reservoir, a spring adapted to move the said brake and release valve into emergency position, pneumatic actuating means moving the said brake and release valve into release, lap and service positions, valved connections connecting the said auxiliary main reservoir with the pneumatic actuating means, and electromagnetic means controlling the said valved connections and controlled by the engineer's valve in the cab of the locomotive.

6. An auxiliary train controlling means, comprising an auxiliary main reservoir mounted on a car in the train and connected with the train pipe to be charged with auxiliary main reservoir pressure, a brake and release valve mounted on the said car and connected with the train pipe and with the said auxiliary main reservoir, a spring adapted to move the said brake and release valve into emergency position, pneumatic actuating means moving the said brake and release valve into release, lap and service positions, valved connections connecting the said auxiliary main reservoir with the pneumatic actuating means, electromagnetic devices controlling the said valved connections, and electric switching means on the said engineer's valve in the cab of the locomotive and connected with the said electromagnetic devices.

7. In an air brake system, a main reservoir on the locomotive, an engineer's valve on the locomotive, a train pipe, an auxiliary main reservoir located on a car in the train and charged from the said main reservoir on the locomotive, a brake and release valve on the said car and connected with the said auxiliary reservoir and the train pipe, and actuating means connected with and controlled by the engineer's valve and actuating the said brake and release valve in unison with the engineer's valve.

8. In an air brake system, an engineer's valve on the locomotive and provided with

a contact arm and with contacts adapted to be engaged by the said contact arm, a train pipe, electromagnetic devices located on a car in the train and electrically connected with the said contacts to operate in unison with the engineer's valve, an auxiliary main reservoir located on the said car, a brake and release valve mounted on the said car and connected with the said auxiliary reservoir and the train pipe, and pneumatic actuating means controlling the said brake and release valve and connected with the said auxiliary main reservoir, the said electromagnetic devices controlling the flow of fluid pressure from the said auxiliary main reservoir to the said pneumatic actuating devices.

9. In an air brake system, an engineer's valve on the locomotive and provided with a contact arm and with contacts adapted to be engaged by the said contact arm, a train pipe, electromagnetic devices located on a car in the train and electrically connected with the said contacts to operate in unison with the engineer's valve, an auxiliary main reservoir located on the said car, a brake and release valve mounted on the said car and connected with the said auxiliary reservoir and the train pipe, pneumatic actuating means controlling the said brake and release valve and connected with the said auxiliary main reservoir, the said electromagnetic devices controlling the flow of fluid pressure from the said auxiliary main reservoir to the said pneumatic actuating devices, and a valved connection connecting the said auxiliary main reservoir with the train pipe to charge the said auxiliary main reservoir with pressure from the main reservoir on the locomotive.

10. In an air brake system, an auxiliary main reservoir on a car in the train, a brake and release valve adapted to move into release, lap, service and emergency positions and connecting the said auxiliary main reservoir with the train pipe, a spring normally holding the said brake and release valve in emergency position, a plurality of pneumatic plungers adapted to move the said brake and release valve into release, lap and service positions against the said spring, valved connections connecting the said auxiliary main reservoir with the said pneumatic plungers, electromagnetic devices controlling the said valved connections, and an engineer's valve provided with circuit opening and closing means electrically connected with the said electromagnetic devices to actuate the latter in unison with the engineer's valve.

11. In an air brake system, an auxiliary main reservoir on a car in the train, a brake and release valve adapted to move into release, lap, service and emergency positions and a brake and release valve connecting

the said auxiliary main reservoir with the train pipe, a spring normally holding the said brake and release valve in emergency position, a plurality of pneumatic plungers 5 adapted to move the said brake and release valve into release, lap and service positions against the said spring, valved connections connecting the said auxiliary main reservoir with the said pneumatic plungers, electro- 10 magnetic devices controlling the said valved

connections, an engineer's valve provided with circuit opening and closing means electrically connected with the said electro-magnetic devices to actuate the latter in unison with the engineer's valve, and means 15 for charging the said auxiliary main reservoir from the main reservoir on the locomotive.

FRANCIS JOSEPH McAVOY.
